UNITED STATES PATENT OFFICE

2,492,558

HOLDING ATTACHMENT FOR JIG VISES

Louis H. Deubler, Jr., Northbrook, Ill., assignor
to James M. Short, Chicago, Ill.

Application May 2, 1946, Serial No. 666,598

2 Claims. (Cl. 77—62)

1

The invention relates generally to a holding attachment for vises or the like particularly adapted for use with a drill or jig vise. The invention has among its objects the production of a holding device adapted to be attached to one of the clamping faces of a vise by means of which cylindrical and other curved or irregularly shaped objects may be efficiently held in position in the vise.

Another object of the invention is the production of such an attachment which may be readily adjusted to accommodate work of various sizes.

A further object of the invention is the production of such an attachment which is simple in construction, relatively inexpensive to manufacture and very efficient in operation.

A further object of the invention is the production of such an attachment which may be mounted on existing vises requiring relatively minor changes to accomplish this result.

The invention is particularly adapted for use on a drill or jig vise such as that shown and described in my U. S. Patent No. 2,315,318, issued on March 30, 1943, and I have illustrated my invention herein as applied to such a vise.

In the drawings wherein like reference characters indicate like or corresponding parts:

Fig. 1 is a top plan view of a vise embodying the present invention;

Fig. 2 is a front elevational view of the vise illustrated in Fig. 1 with a portion of the upper clamping member and one of the holding blocks broken away to disclose details thereof; and

Fig. 3 is a perspective view of one of the holding blocks.

The vise illustrated in the drawings broadly comprises a base, indicated generally by the numeral 1, having threaded uprights 2 slidably mounted thereon, the uprights 2 having a clamping plate 3 secured thereto. The plate 3 is provided with apertures therein through which the uprights 2 extend, the latter being locked in position by the nuts 4. A lever 5 is secured to an operating shaft 6 which is operatively connected to the uprights 2 whereby the latter may be moved upwardly or downwardly to clamp an object between the plate 3 and the opposing face 7 of the base portion 1, the mechanism for accomplishing this result being described in the reference patent.

Secured to the inner face of the plate 3 is a pair of blocks designated generally by the numeral 8, the base 9 of each block having a longitudinally extending tongue 10, of rectangular

cross section, extending therefrom, each tongue being seated in a similarly shaped groove 11 in the adjacent face of the plate 3, the blocks being securely held in position by suitable bolts 12 passing through holes in the plate 3 and threaded into the tapped holes 13 in the respective blocks. As the tongues 10 and cooperating grooves 11 have parallel edges, the blocks may be reversely positioned on the plate.

10 Each block is constructed with a pair of inclined face portions 14 and 15 respectively which, in the embodiment of the invention illustrated, are inclined towards one another, each at an angle of substantially forty-five degrees with the base 9.

15 It will be noted that the portion 14 is greater in width than the portion 15, the latter being spaced farther from the base 9 than the portion 14 with the intermediate face 16 being substantially vertical to the base 9. Thus when the blocks are positioned as illustrated in Fig. 2 with the face portions 14 in opposed relation, a relatively large piece of work such as a cylinder, indicated in dotted lines in Fig. 2, may be clamped between the portions 14 and the face 7 of the vise.

20 When it is desired to clamp a smaller piece of work, such as a smaller cylinder, indicated in dotted lines in Fig. 2, the blocks may be reversed as indicated in dotted lines, so that the smaller piece of work may be readily clamped in the vise between the portions 15 and the face 7 without changing the adjustment of the plate 3, as the juncture of the planes of the portions 15 will be spaced a greater distance from the face of the plate 3 than the juncture of the planes of the face portions 14 when the latter are in opposed relation. Thus the reversal of the blocks, in effect, operates to increase or diminish the work receiving space between the respective inclined portions and the opposite vise face.

25 The vise illustrated is provided with an aperture 17 in which is seated a removable flanged sleeve 18 adapted to align a drill or other tool for application thereof to the work being held in the vise, the size of the bore 19 of the sleeve 18 depending upon the size of the tool employed. To permit engagement of such a tool with the work held in the vise, the blocks 8 are provided with recesses 21 and 22, the recesses 21 of the respective blocks being aligned with the bore 19 when the blocks are in the position illustrated in Fig. 2 with the face portions 14 in opposed relation, thereby providing clearance for any tool 30 inserted into the bore 19 of the sleeve. Likewise

the recesses 22 are aligned with the bore 19 when the blocks are reversed into the position illustrated in dotted lines in Fig. 2 with the face portions 15 in opposed relation. As the blocks, when in the latter position, are adapted to engage smaller work than when in their other position the recesses 22 may be smaller in depth than the recesses 21 as obviously a smaller sized tool would generally be employed for use on the smaller work, in which case the sleeve 18 will be provided with a smaller sized bore 19 than the sleeve adapted for use with the blocks in their illustrated position. It will be apparent that when the blocks are in either of their respective positions, the tongues 10 and grooves 11 prevent any lateral displacement of the blocks when clamping a piece of work so that similar pieces of work will be always held in exactly the same position in the vise with respect to the sleeve.

By providing the blocks 8 with two faces having inclined face portions of different widths, the two blocks illustrated will accommodate a very large percentage of the different sizes of work adapted to be held in the vise and will eliminate the necessity of providing a series of blocks for different sizes of work, thereby reducing tooling costs, etc.

It will be apparent that the blocks 8 may be readily mounted on existing vises by merely milling grooves into one of the clamping faces of the vise on which it is to be installed, of a size to receive the tongues 11 of the respective blocks, and providing holes for the mounting bolts 12.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a holding attachment for a clamping device or the like having opposed clamping and work engaging faces, the combination of a pair of like opposed blocks, means on the base of each block engageable with cooperating means on said clamping face of the clamping device for rigidly attaching the blocks thereto in any one of a plurality of positions, whereby different side faces of the respective blocks may be positioned in opposed relation, said clamping face having a tool receiving aperture therein between said blocks, the respective side faces of each block having longitudinally extending portions of different

widths inclined with respect to the base thereof, so that by varying the positions of the blocks relative to each other, articles of different sizes may be engaged by one of the inclined portions of each block and the work engaging face of the clamping device, each of said blocks having recesses therein, alignable with said aperture to permit a tool inserted in said aperture to pass between said blocks when the latter are in their various positions.

2. In a holding attachment for a clamping device or the like having opposed clamping and work engaging faces, the combination of a pair of opposed blocks, means including a tongue on the base of each block engageable with a corresponding groove in said clamping face of the clamping device for rigidly attaching each block thereto, said tongues being reversible in their respective grooves whereby different side faces of the respective blocks may be positioned in opposed relation, said clamping face having a tool receiving aperture therein centered between said blocks, the respective side faces of each block having longitudinally extending portions of different widths, the narrowest portion being spaced farther from the base than the widest portion, said portions being inclined towards each other, each at an angle of substantially 45 degrees with respect to the base, so that relatively large articles may be engaged by the wide portions of the blocks and the work engaging face of the clamping device, when the blocks are in one position, and relatively small articles may be engaged by the narrow portions of the blocks and the work engaging face of the clamping device, when the blocks are in a reversed position, each of said blocks having recesses therein alignable with said aperture to permit a tool inserted in said aperture to pass between said blocks when the latter are in their various positions.
